UNITED STATES PATENT OFFICE.

FRED H. KNAPP, OF CHICAGO, ILLINOIS.

SHADE ADJUSTMENT.

SPECIFICATION forming part of Letters Patent No. 707,240, dated August 19, 1902.

Application filed November 16, 1901. Serial No. 82,550. (No model.)

To all whom it may concern:

Be it known that I, FRED H. KNAPP, a citizen of the United States, residing at Chicago, in the county of Cook and State of Illinois, 5 have invented new and useful Improvements in Shade Adjustments, of which the following is a specification.

My invention relates particularly to shade adjustments of the general nature of those described in my Patent No. 668,800, February 26, 1901, and that of Clarence W. Blackstone, assignor, No. 674,331, May 14, 1901.

My primary object is to provide means for controlling the movement of the free end of 15 a curtain which is as a whole vertically adjustable.

My invention is shown in the preferred form in the accompanying drawings, in which—

Figure 1 is a broken elevational view of a 20 window equipped with an adjustable shade to which my present improvements have been applied; Fig. 2, a broken vertical section, taken as indicated at line 2 of Fig. 3 and showing a connection between a lower shade-corner and a guide-rod; Fig. 3, a transverse section at line 3 of Fig. 2; Fig. 4, a vertical section at line 4 of Fig. 3; Fig. 5, a horizontal section at line 5 of Fig. 4, and Fig. 6 a detached plan view of a combined intermediate 25 guide-rod bracket and slide-stop employed.

A represents a window-frame; B, upper stationary combined guide-rod and pulley-brackets of the kind described in said Patent No. 668,800; C, guide-rods connected with 30 said brackets; D, sliding shade-roller brackets of the kind described in said Patent No. 674,331; E, a shade-roller bearing a shade E'; F, cords connected with the brackets D and passing over pulleys a in the brackets B, said 35 cords uniting in a cord F', connected with a cord-stop F², the latter constituting a separate invention, described and claimed in my pending application, Serial No. 84,648, filed December 4, 1901; G, intermediate combined 40 guide-rod brackets and slide-stops, and H connections between the lower corners of the shade and the guide-rods.

The connections H and the arrangement of the slide-stops G constitute the chief features 45 of novelty of the present application.

A bracket G is clearly shown in Fig. 6, from which it will be understood that the bracket

embraces the guide-rod and is secured to the window-frame, affording a firm fixture. The lower ends of the guide-rods are secured to 55 the window-frame in any suitable manner. (Not shown.)

Each connection H comprises, preferably, a shade-carried slide-supporting member H' and a slide H², provided with a pivoted tongue H³, freely entering a socket in the member H' and serving as a means for moving said slide. The shade-carried part H' comprises a sheet-metal clip bent to triangular shape to fit the lower wooden binding-strip b of the shade, 65 said clip being firmly secured in place by inwardly-stamped prongs b', engaging the lower edge of the strip b, and a pin or rivet b², passing through the upper portion of said strip. The prongs b' are so located as to afford beneath them a recess or socket b³ for the tongue 70 H³. The slides H² comprise short tubes which fit loosely on the guide-rods and are provided with pivotal lugs connected by pins c with the tongues H³, the latter being slotted to receive the lugs. The tubes may be of pressed 75 wood fiber or other material of a suitable nature to avoid objectionable rattling on the guide-rods, or felt washers c', held in place by caps c², may serve the same purpose. 80 Likewise any suitable expedient may be adopted to prevent the tongues H³ from rattling, while not interfering with the requisite freedom of movement within the sockets b³.

The operation will be understood readily. 85 The shade-roll E may be adjusted to any desired vertical height through the medium of the cord F'. It may be dropped till the brackets D encounter the brackets G, in which case the shade may be drawn to cover the 90 lower window, or, assuming the roll to be just above the bracket G and the curtain to be rolled up till the slides H² engage the brackets G, the roll may be raised to any desired 95 height, in which case the shade will by the same action be unwound to cover the upper window. Thus it will be seen that the brackets G serve in this latter operation to hold the lower end of the shade depressed while the roll is raised, causing the roll to revolve. 100

Within the limits of their traverse the slides H² move freely on the guide-rods, and binding is prevented by the relative movability in a plane parallel with the shade of the parts

of the connection between said slides and the shade. Objectionable swaying of the lower end of the shade is prevented, and the expedient permits the use of adjustable rolls in proximity to lace curtains without danger of injury to the latter. Moreover, the curtain is guided properly in winding on its roll, so that fraying of its edges is prevented. It will be noted that this feature is of advantage with shades having non-adjustable rolls.

Suitable muffling-washers (not shown) may be used in connection with the brackets G, if desired to prevent noise when either the slides H² or the sliding brackets D encounter the fixed brackets G.

Changes in details of construction within the spirit of my invention may be made. Hence no undue limitation is to be understood from the foregoing detailed description.

20 What I claim as new, and desire to secure by Letters Patent, is—

1. In a device of the character described, a shade provided at one end with suitable actuating means, vertical guide-rods, and guiding means for the free portion of the shade, comprising slides on said rods, and slide-supporting means on said shade near the free end thereof and engaging said slides, the slide and slide-supporting means of each set being capable of relative movement in a plane parallel with the shade, substantially as described.

2. In a device of the character described, a shade provided at one end with suitable actuating means, vertical guide-rods, and guiding means for the free portion of the shade, comprising slides on said rods, and slide-supporting means on said shade near the free end

thereof and engaging said slides, one of said last-named parts of each set bearing a pivoted tongue and the other a recess for receiving said tongue, substantially as described.

3. In a device of the character described, a shade suitably attached at one end, guide-rods, and guiding means for the free part of the shade, comprising slide-supporting members connected with said shade, and having suitable recesses, and slides on said guide-rods provided with pivoted tongues engaging said recesses, substantially as described.

4. In a device of the character described, a shade provided at one end with suitable actuating means and at the opposite end with a binding member, clips connected with said shade at said binding member and forming sockets beneath said member, guide-rods, and slides on said rods having projections engaging said sockets, substantially as described.

5. In a device of the character described, the combination of vertical guide-rods, roll-supporting slides connected therewith, a roll supported from said slides, and bearing a shade, slides connected with said rods and with the shade near its free end, fixed slide-stops intermediate said first-named slides and said second-named slides, and means for actuating said roll-supporting slides, whereby the roll may be raised and the shade drawn at one operation, substantially as and for the purpose set forth.

FRED H. KNAPP.

In presence of—
ALBERT D. BACCI,
M. S. MACKENZIE.
